UNITED STATES PATENT OFFICE.

THEODOR BIRATH, OF JERSEY CITY, NEW JERSEY, ASSIGNOR TO MANHATTAN ELECTRICAL SUPPLY COMPANY, OF JERSEY CITY, NEW JERSEY, A CORPORATION OF NEW JERSEY.

LAMP-CARRIER.

1,137,568.

Specification of Letters Patent. Patented Apr. 27, 1915

Application filed October 1, 1914. Serial No. 864,480.

To all whom it may concern:

Be it known that I, THEODOR BIRATH, a citizen of the United States, residing at Jersey City, in the county of Hudson and State of New Jersey, have invented certain new and useful Improvements in Lamp-Carriers, of which the following is a specification.

This invention relates to lamp-carriers.

10 A lamp-carrier involving my invention can be used with advantage in many different connections, although it is of peculiar utility when employed in conjunction with a so-called "dry-cell battery", in that by 15 it such latter article can be converted into a lamp. A lamp-carrier made in accordance with my invention is simple in construction, susceptible of inexpensive manufacture and is highly effective in action. I have indicated one of its several uses, and when so 20 employed it may be associated with the battery in any desirable manner, although I prefer that when so utilized it be in the nature of an attachment; that is to say, it is 25 capable of detachable connection therewith.

In the drawings accompanying and forming part of the present specification I have shown in detail one of the several convenient forms of embodiment of the invention, 30 which to enable those skilled in the art to practise the same will be set forth fully in the following description. I do not restrict myself to this disclosure; I may depart therefrom in several respects within the 35 scope of the invention defined by the claims following said description.

Referring to said drawings: Figure 1 is a detail view in side elevation of a lamp-carrier involving my invention and showing the same connected with a dry-cell battery. Figs. 2 and 3 are inside and outside face views of the lower portion of one of the branches of the body of the lamp-carrier. Fig. 4 is a vertical sectional view of the intermediate portion of the lamp-carrier and illustrates by full and dotted lines, the two positions of the button. Fig. 5 is a similar section of the lower portion of one of the branches of the body, showing the button in the position it is illustrated as occupying by dotted lines in Fig. 4. Fig. 6 is a detail view showing part of a battery with the binding posts differently positioned from that shown in Fig. 1 and the lamp-carrier connected with said parts.

Like characters refer to like parts throughout the several views which it will be noted are on different scales.

In Fig. 1 I have shown a dry-cell battery 2 of familiar construction, the same having binding-posts 3 and 4 constituting convenient terminals and both vertically disposed. In Fig. 6 the battery 5 has its posts at right angles to each other, the post 6 as shown being horizontal while the post 7 is vertical, the lamp-carrier being of such nature as to be adapted for connection with either style of battery. As a matter of fact the device can be connected with any other suitable battery or similar source of electrical energy. The binding-posts as will be inferred present a suitable means for the detachable connection of the lamp-carrier with the battery. Said lamp-carrier involves in its make-up a body portion such as that denoted in a general way by 8 and I prefer to employ in connection therewith a suitable handle which as shown consists of a bail 9 pivotally connected as will hereinafter more particularly appear with the body portion 8. As represented said body portion consists of two branches or brackets as 10 and 11 respectively of some suitable electric conducting material such as brass, these branches being connected together at their upper ends in some convenient way as by the rivet 12 which presents a suitable pivot for connecting the bail 9 with said branches, the pivot extending through said branches and also through downturned lugs 9' of the loop-like bail 9, insulating strips or disks as 13 being interposed between the lugs 9' and said branches 10 and 11 from which it will be apparent that the bail or handle is insulated from the body 8 and that said branches are insulated from each other.

One of the branches as the branch 10 sustains a lamp while the other supports a switch co-operative with but normally insulated from the lamp and which switch may consist of a contact-spring, all as will hereinafter more particularly appear. The branches 10 and 11 have outwardly-extending angular feet 14 and 15 respectively, the foot 14 having a hole or perforation 16 to receive the binding-screw 3, while the foot 15 has a slot 17 to adjustably receive the binding-screw 4 of the battery 2. (Fig. 1). To connect the carrier with said battery the nuts of the binding posts 3 and 4 are re-

moved, after which said binding posts are passed respectively through the perforation 16 and slot 17 when the nuts are reapplied and set to clamp the lamp carrier substantially in place. The branch 10 has adjacent to the foot 14 and in its upright portion the slot 18 to receive the binding-post 6 of the battery 5 while the slot 17 receives the binding post 7 of said battery 5 when the lamp carrier is to be connected therewith as shown in Fig. 6.

The lamp 19 is provided with the customary contact-shell 20 and central end contact 21, said shell as usual being externally threaded and being adapted to be threaded into the rearwardly-extending boss 21' of the reflector 22 which as shown is of parabolic form. The branch 10 sustains the reflector 20 and as illustrated is provided between its ends, with the internally-threaded boss 23 to be engaged by the external threads of the boss 21' of the reflector, the internal threads of which receive those of the contact-shell 20. The branch 10 is so shaped that when the boss 21' of the reflector is fully seated in the boss 23 of the branch 10 and when the shell 20 is all the way in, the central end contact 21 of the lamp 19 will be separated or spaced comparatively a short distance from the branch 11. In this space a switch such as I have briefly referred to may be located. The contact-spring 24 answers satisfactorily in this connection, said contact-spring 24 being fastened by riveting or otherwise at its butt below the elongated slot 25 in the branch 11, this spring contact by its resiliency being normally sprung away from the central end contact 21 to thus present a break in the circuit including the lamp 19, it being understood that there is an electrical connection between the shell 20 and boss 21' and between the boss 21' through the boss 23 with the branch 10 which in turn is electrically connected with the post 3 or post 6 as the case may be, while the branch 15 electrically connected with the contact spring is adapted to be connected electrically with either the post 4 or post 7. It, therefore, follows that if the carrier be connected with a battery in the manner indicated and the spring contact 24 be pressed against the central end contact 21, the lamp 19 will be lighted.

To operate the spring contact 24 the button 26 may be utilized, said button having a flat bearing and sliding engagement against the outer surface of the branch 11, the shank 27 of the button being movable longitudinally of the slot 25. The shank 27 has at its inner end the semi-spherical

head 28 coöperative with the spring contact 24 as will hereinafter appear to prevent accidental removal of the button 26. The lower part of the slot 25 as shown is circular as at 29, the diameter of the circle 65 slightly exceeding the diameter of the head 28, so that in assembling the parts the head 28 can be passed through the circular hole 29 and the shank 27 afterward entered in the straight or main part of the slot 25. The 70 spring contact 24 is provided near its base with the bent portion 30 which receives the head 28 when the shank 27 has practically reached the lower end of the slot 25 to thus hold the button against accidental displacement. When the button 26 is in the full line position in Fig. 4 it permits the spring-contact 27 to move by its resiliency away from the central end contact of the lamp 19. By lowering the button 26 to the dotted line 80 position in Fig. 4 or as shown in Fig. 5, the head 28 will ride along the cam-portion 31 of the spring contact 24 to thus force the free portion of said contact against the end contact 21 to light the lamp provided the 85 carrier be connected in the manner described with the battery 2 or with the battery 5.

What I claim is:

A lamp carrier comprising a body portion 90 having a lamp carrying branch and a contact carrying branch, insulated from each other and having means for the detachable connection with the terminals of a battery, a spring contact on the contact carrying 95 branch, the latter having a longitudinal slot, one end of which is circular, a button 100 slideable against said contact carrying branch, said button having a shank provided with a head, the diameter of the head being less than that of said circular portion of said slot, said shank being slideable in the slot, the button being contiguous to one side of said contact carrying branch and the head being contiguous to the other side thereof, the button being adapted to engage said spring contact on one movement of the button to move said contact into circuit closing position, and said spring contact having a portion to receive said head 110 before said shank enters said circular portion to thereby prevent accidental displacement of the button.

In testimony whereof I affix my signature in presence of two witnesses.

THEODOR BIRATH.
